VOLUMETRIC FEEDER

James M. Montgomery, New York, N. Y., assignor
to The Permutit Company, New York, N. Y., a
corporation of Delaware

Application July 15, 1937, Serial No. 153,842

10 Claims. (Cl. 210—29)

This invention relates to volumetric feeders; and it comprises apparatus for measuring and dispensing definite volumes of fluent materials, comprising a hopper adapted to contain a quantity of such materials, means providing an opening in communication with the lower part of the hopper, an oscillating closure for the hopper bottom so constructed and arranged that upon oscillation of the closure definite quantities of the material are dispensed through the opening, a motor, crank means connecting the closure and the motor so constructed and arranged that upon rotation of the motor the closure is oscillated, stationary means for varying the effective throw of the crank means, oscillating scraper means in the hopper, and power transmitting crank means connecting the motor with the scraper means, additional electrical control means sometimes being provided; all as more fully hereinafter set forth and as claimed.

In many chemical operations it is necessary to feed successive portions or dosages of solid materials at some definite rate, or in some definite proportion, to a flow of fluid. For example, in water treatment it is necessary to feed softening agents, coagulating agents or other material, to a flow of water in predetermined proportions. Many types of apparatus have been devised for this purpose and some have come into wide use. Feeding granular solids volumetrically and accurately presents difficulties. Solids will flow somewhat like liquids if the solids are in the form of discrete granules or particles and if they are kept in that condition as by agitation. In general, the harder, smoother, drier, coarser and more nearly spherical the particles are, the more readily they will flow. But there is always a tendency for the granular solids to arch or cling in the feed hopper.

According to the present invention there is provided a volumetric dry feeder which is capable of accurately dispensing measured volumes of pulverulent or granular solid materials, such as lime, activated carbon, soda ash, alum, etc. The apparatus is well adapted for handling a wide variety of materials, including some which are otherwise particularly difficult to dispense volumetrically. The apparatus is also readily adapted for adjustment of the proportions dispensed; adjustment even while the apparatus is in operation. The apparatus comprises a feed hopper provided with scraper-like agitators operated by a motor which also drives the dispensing mechanism proper. The dispensing mechanism comprises a swinging closure adapted to be oscil-

lated or reciprocated by the same motor and in reciprocating, to feed portions of the solid material out from the hopper. Adjustable link means are provided so that the length of travel by the swinging arcuate closure may be adjusted during use by manipulating a stationary handle.

In the accompanying drawings there are shown more or less diagrammatically three examples of specific embodiments of apparatus within the purview of the invention. In the showings,

Fig. 1 is a side elevation of one apparatus;

Fig. 2 is an end elevation;

Figs. 3 and 4 are diagrammatic views to show the operation of the dispensing mechanism;

Fig. 5 is a detailed elevation view showing an optional agitator means;

Fig. 6 is a side elevation showing a modification having electrical control means;

Fig. 7 is an end elevation of the apparatus of Fig. 6;

Fig. 8 is a detail view of a portion of the apparatus of Figs. 6 and 7;

Figs. 9 to 12 are diagrams of the electrical circuits of the apparatus shown in Figs. 6 and 7;

Fig. 13 is a detail view of one of the scrapers of Figs. 1 and 2.

In the drawings, Figs. 1 and 2 show the complete apparatus. The apparatus is located inside a dustproof case 10. A hopper 11 is provided in the form of the frustum of a pyramid, and having a rectangular extension 12 at the bottom. The hopper is adapted to contain a batch of granular or pulverulent solid material 17. An arcuate closure 13 is arranged to cover the bottom of this extension. One end wall 121 of the extension is spaced above the arcuate closure defining an opening 14 as shown in Figs. 3 and 4. The side walls 122 extend below the end wall 121 and terminate in arcs adjacent the closure 13. The arcuate closure is mounted on a shaft 15 and is arranged for reciprocation by an arm 16. The operation of these members will be clear from Figs. 3 and 4. Upon movement of the closure to the right (Fig. 3), granular material 17 is drawn out on to the closure through opening 14. Upon movement of the closure to the left, the solid material cannot be forced backward into the hopper, but spills over the edge of the closure as shown in Fig. 4.

A motor 20 with integral gear reduction is provided for operating the apparatus. The motor shaft has a crank 21 with an enlarged crank pin 22. A lever 23 slotted at 24 engages the crank 21. The opposite end of the lever 23 is pivoted as at 25

25 to a sliding block 26 which is threaded and which is adapted to be shifted up and down by a screw 27 provided with an adjusting knob 28. Lever 23 is joined with arm 16 by a link 29 and 5 pivot pins 30 and 31. The distance between pivot pins 30 and 31 is advantageously equal to the distance between pivot pins 25 and 30. Upon rotation of the motor the arcuate closure is reciprocated by the mechanism shown. In Fig. 1, the apparatus is shown adjusted for almost a maximum feed rate. By screwing block 26 upward, the feed rate becomes less until when pivot 25 in block 26 is coaxial with pivot 31 the feed rate becomes zero. The adjusting means remains 15 stationary so that periodic adjustment of the feed rate is made possible while the apparatus is in operation.

The apparatus is provided with scraper-agitator means comprising four scrapers each 20 consisting of a rod 35 having a plurality of V-shaped members 36 mounted thereon. The rods ride in the four corners of the hopper and the V-shaped members scrape the sides as shown. The upper ends of the rods are attached to arms 25 37 which are fixed to a shaft 38 mounted in bearings 39 near the upper part of the hopper. A long arm 40 is affixed to the shaft and has a slot 41 at its outer end engaging crank pin 22. Thus by rotating the motor the agitator is operated. 30 This agitator proves to be very successful in handling most kinds of solid materials. It prevents arching and clinging. A sliding gate 42 is provided so that the hopper supply can be shut off if desired.

35 The motor and adjustment means are mounted on a casing 43 having an inspection door 44. The lower end of the casing communicates with a wash hopper 45 arranged to receive material dropping from the feed hopper. An inlet pipe 40 46 and an outlet pipe 47 are provided for liquid to be dosed and for the mixture respectively. A perforated spray pipe 48 is arranged inside the hopper and is supplied with liquid under pressure to wash material into the lower portion of 45 the hopper.

While the agitating means shown in Figs. 1 and 2 is of wide utility, with certain substances, such as moist alum, it is sometimes better to provide a vibrating hammer. Such an arrangement is shown in Fig. 5. A hammer 50 having a rubber striking face 51, is mounted on a shaft 52 pivotally mounted on the casing 43. A tension spring 54 connected to the hopper and to the hammer tends to force the striking face against 50 the side of the hopper. In place of the spring, other means can be used to force the hammer against the hopper, such as a weighted arm on the hammer. The shaft has a crank arm 53, so arranged as to be struck by the rotating crank pin 22. During each revolution of the crank pin the hammer strikes the hopper a blow and dislodges any material from the sides. The hammer can be used in addition to the reciprocating scrapers if desired.

65 The various parts of the apparatus which come into contact with the solids and liquids are made of materials adapted to resist attack.

In operation, the device feeds solids accurately and reliably. Arching and clinging are minimized and the top surface of the mass of solids in the hopper stays practically level.

70 The device described operates as a constant rate feeder, the rate being adjustable by means of adjustment knob 28 or the motor speed or 75 both. The apparatus is readily adaptable for use

as a proportional feeder controlled by a water meter or the like. Figs. 6 and 7 show how this is done.

Referring to Figs. 6 and 7, there is provided a bracket 60 on the casing 43, having a sector plate 61 integral therewith and a bearing 62 adapted to receive a shaft 63 mounted for rotation therein. Mounted on the shaft is a ratchet-toothed wheel 64 adapted to be advanced by a pawl 65 pressed against the wheel by spring 66 and pivotally mounted on the arm 67 which is journaled on the shaft. Arm 67 is connected by link 68 to lever 23. Thus upon rotation of the motor the toothed wheel 64 is caused to advance. A pawl 59 pivoted to bracket 60 is arranged to prevent backward motion of the ratchet wheel. At the outer end of the shaft is positioned a crank arm 68a having a crank pin 69 sliding in an elongated slot 70 of an arm 71 pivotally attached to sector plate 61 by a pivot 72. Thus upon rotation of wheel 64 arm 71 is caused to oscillate in a vertical plane. Attached to the arm by clips 73 is a three-point mercury switch having a glass tube 74 with three contact elements 75, 76 and 77 extending therein and containing a body of mercury 78.

The construction of arm 71 will be clear from Fig. 8, which shows the arm and operating means alone, the switch being omitted from Fig. 8 for the sake of clarity of presentation.

The three contact elements are connected to three wires 79, 80 and 81. Upon oscillation of arm 71, the switch is alternately tipped to the right and to the left, it is shown in central position in Fig. 7. Means are provided for adjusting the relative moment of wheel 64 under the influence of the pawl. This comprises a cam 82 floating on shaft 63 and adapted to be set in various angular positions by a springy handle 83 having a pin 84 adapted to rest in any one of a plurality of holes 85 in the sector plate. When the handle is set at the extreme right, the cam does not interfere with the pawl 65 and on each rotation of the motor shaft, wheel 64 is advanced a plurality of teeth; in this case 12 teeth. With the handle in the position shown in Fig. 7, during part of the time a pin 88 on pawl 65 simply rides on cam 82 and hence lost motion is provided; the wheel is advanced only 7 teeth on each revolution of the motor. With the handle at the extreme left, the pin 88 rides on cam 82 all the time and the wheel is not advanced. This in effect puts the mercury switch out of operation. The feeder, once started, will operate continuously.

The electrical connections are shown in Fig. 7. A water meter is provided as shown at 90, having a rotary shaft 91 carrying a cam 92. An oscillating fork 93 is pivotally attached to the meter as at 94 and it rides on the cam. Upon rotation of the meter shaft the fork is alternately shifted left and right. It is held in each of the two positions by a snap spring 95. Fork 93 carries a mercury switch 96 similar to switch 74 and having three contacts 97, 98 and 99. Contacts 97 and 99 are attached through wires 100 and 101 to wires 81 and 78 respectively. Contact 98 is in communication through wire 102 with a source of electrical energy, not shown, such as an ordinary 110 volt A. C. line. Contact 76 of the 70 motor switch 74 is connected through wire 88 and a wire 103 with the motor. The other side of the motor is connected to the source of energy through a wire 104.

Referring to Figs. 9 to 12, Fig. 9 shows the con- 75

- nections just after the meter switch has moved to one of its two positions. The motor switch is in the position shown and a circuit is established through the motor as shown in heavy lines. The motor runs, and solids are fed. In due course, wheel 64 is advanced sufficiently to shift the motor switch to its other position, as shown in Fig. 10. The meter switch remains as before and the circuit is dead. In the course of time, after passage of a predetermined gallonage of water, the meter switch is moved to its other position, as shown in Fig. 11, and a new motor circuit is established, as shown by heavy lines, and solids are fed. This keeps up until the motor switch is shifted, as described before, whereupon the circuit goes dead (Fig. 12). The circuit is now ready for a new cycle of operations, upon shifting of the meter switch again to the position shown in Fig. 9.
- 20 The various parts of the mechanism are so designed that the motor switch always shifts before the meter switch is shifted; thus the meter always does the controlling.
- 21 What I claim is:
- 22 1. Apparatus for measuring and dispensing fluent materials volumetrically, comprising a hopper adapted to contain a quantity of such materials and having a bottom portion including two side walls arcuate about a horizontal axis adjacent one end of the hopper, an end wall adjacent said end and extending down to a level above the lower termination of the arcuate walls, and an opposite end wall, an arcuate, oscillatable closure pivotally supported so as to swing about said axis and engaging the lower terminations of said arcuate walls to close off the hopper bottom against downward flow, whereby on oscillation of the closure measured quantities of materials are dispensed, a link pivotally connected to the closure, eccentric with respect to the axis thereof, for oscillation of the closure, a lever pivotally connected to the link, a fulcrum for the lever, a motor, means operatively connected to the motor for oscillating the lever about said fulcrum, and stationary means for adjusting the relative position of said fulcrum with respect to the link, whereby to permit adjustment of the quantity of material dispensed by the closure at each oscillation thereof.
- 23 2. Apparatus for measuring and dispensing fluent materials volumetrically, comprising a hopper adapted to contain a quantity of such materials and having a bottom portion including an end wall and two side walls having lower edges extending below said end wall, a member adjacent the lower edges of the side walls for dispensing chemicals, a shaft for said member, bearings in which said shaft is oscillatable, an arm having one end attached to said shaft, a motor, a crank rotatable by the motor, a lever having near one end an elongated slot adapted to engage said crank and a pivot near its other end, a link connecting the other end of said arm with a point on the lever, the distance between said point and said pivot being equal to the length of said link, a block connected with said pivot, and means for moving said block.
- 24 3. The apparatus of claim 2, said last named means comprising a threaded opening in said block, a screw in said opening, bearing means for said screw permitting rotation without axial movement, and a handle attached to said screw.
- 25 4. Apparatus for measuring and dispensing fluent materials volumetrically, comprising a hopper adapted to contain a quantity of such
- 26 materials and having a bottom portion including an end wall and two side walls having lower arcuate edges extending below said end wall, an arcuate member pivotally supported to oscillate below the arcuate edges of the side walls and adapted to dispense a definite quantity of material upon each oscillation of said member, a motor, a rotating eccentric element driven by the motor, means operatively connecting the rotating eccentric element with said member so that the motor is adapted to oscillate the member, means for adjusting the throw of said connecting means, and therefore the quantity of material dispensed upon each oscillation of the member, a plurality of scraper elements inside the hopper arranged for up and down movement therein, and means operatively connecting said scraper elements with the motor-driven eccentric element so that the scraper elements are moved up and down by the motor.
- 27 5. In an apparatus for measuring and dispensing fluent materials volumetrically, a hopper adapted to contain a quantity of such materials, an opening in communication with the lower part of the hopper, a closure below said opening adapted to be moved back and forth and so arranged that upon each back and forth movement thereof a predetermined volume of material is dispensed through the opening, a motor, means driven by the motor and being adapted to move said closure back and forth, a pivotally mounted hammer having a resilient striking face, resilient force-applying means tending to move said hammer against a wall of the hopper, an arm connected with the hammer, and a member in said motor driven means arranged to alternately engage and disengage said arm during each back and forth movement of said closure and thereby to alternately move the striking face away from the hopper to be moved back toward the hopper by the resilient means upon disengagement of the member from the arm.
- 28 6. In an apparatus for measuring and dispensing fluent solid materials volumetrically in proportion to a flow of liquid, comprising a hopper adapted to contain a quantity of such materials, an opening in communication with the lower part of the hopper, a closure below said opening adapted to be moved back and forth and so arranged that upon each back and forth movement thereof a predetermined volume of material is dispensed through the opening, an electric motor, means driven by the motor and being adapted to move said closure back and forth, and a meter adapted to measure the flow of liquid, an improved automatic control which comprises a cut-out switch operatively connected to said motor driven means to interrupt a circuit after a predetermined number of back and forth movements of the closure, a starting switch operated by the meter to establish a circuit after a predetermined quantity of liquid has passed through the meter, a source of electric energy, and electrical connections interconnecting the source of electric energy, the motor and said switches.
- 29 7. In an apparatus for measuring and dispensing fluent solid materials volumetrically in proportion to a flow of liquid, comprising a hopper adapted to contain a quantity of such materials, an open bottom for the hopper, an opening in communication with the lower part of the hopper, an oscillating closure for the hopper bottom so constructed and arranged that upon each oscillation of the closure a definite volume of the material is dispensed through the opening, an

- electric motor, a crank rotatable by the motor, means connecting the crank with the oscillating closure, and a meter adapted to measure the flow of liquid an improved automatic control which comprises a cut-out switch, a ratchet wheel for operating the cut-out switch, a pawl adapted to move the ratchet wheel, a linkage connecting said connecting means and the pawl for oscillating said pawl and thereby to move the cut-out switch 10 to interrupt an electric circuit after a predetermined number of oscillations of the closure, a starting switch operable by the meter to establish an electric circuit after a predetermined quantity of liquid has passed through the meter, 15 a source of electric energy, and electrical connections interconnecting the source of electric energy, the motor and said switches.
8. In the apparatus of claim 7, an adjustable cam adapted to prevent the pawl from moving the ratchet wheel during part of each oscillation of the pawl for the purpose of adjusting the number of oscillations of the closure after which the cut-out switch interrupts the electric circuit.
9. In an apparatus for measuring and dispensing fluent solid materials volumetrically in proportion to a flow of liquid, comprising a hopper adapted to contain a quantity of such materials, an open bottom for the hopper, an opening in communication with the lower part of the hopper, 20 an oscillating closure for the hopper bottom so constructed and arranged that upon each oscillation of the closure a definite volume of the material is dispensed through the opening, an electric motor, a crank rotatable by the motor, means connecting the crank with the oscillating closure, and a meter adapted to measure the flow of liquid, an improved automatic control which comprises a three-point switch adapted to be moved by the motor from position to position every time the motor has made a predetermined number of revolutions, a second three-point switch adapted to be moved by the meter from position to position every time a predetermined quantity of liquid

has passed through the meter, a source of electric energy, and electrical circuits series-connecting the motor and said three-point switches with the source of electric energy, each movement of said second three-point switch by the meter being adapted to establish a circuit energizing the motor and each movement of the first three-point switch by the motor being adapted to interrupt a circuit, thereby de-energizing the motor.

10. In an apparatus for measuring and dispensing fluent materials volumetrically, comprising a hopper open at the bottom and adapted to contain a quantity of such materials, an oscillating closure for the hopper bottom so constructed and arranged that upon oscillating the closure 15 definite quantities of the material are dispensed, a motor, a lever one end of which is oscillated by the motor, link means connecting the lever with the oscillating closure, a pivot for the other end of the lever, stationary means for adjusting the position of said pivot with respect to the link means whereby to permit adjustment of the quantity of material dispensed by the closure at each oscillation thereof, and a meter adapted to measure a flow of liquid, an improved automatic 20 control which comprises a three-point switch adapted to be moved by the motor from position to position every time the motor has made a predetermined number of revolutions, a second three-point switch adapted to be moved by the 25 meter from position to position every time a predetermined quantity of liquid has passed through the meter, a source of electrical energy, and electrical circuits series-connecting the motor and said three-point switches with the source of electric 30 energy, each movement of said second three-point switch by the meter being adapted to establish a circuit energizing the motor and each movement of the first three-point switch by the motor being adapted to interrupt a circuit, there- 35 by deenergizing the motor.

JAMES M. MONTGOMERY.
